UNITED STATES PATENT OFFICE.

AXEL JOHNSON, OF OAKLAND, CALIFORNIA.

ELECTRIC HEATER.

Application filed November 19, 1923. Serial No. 675,451.

To all whom it may concern:

Be it known that I, AXEL JOHNSON, a citizen of the United States, residing at Oakland, in the county of Alameda and State of California, have invented certain new and useful Improvements in Electric Heaters, of which the following is a specification.

Electric heaters heretofore manufactured have usually been either of the radiation type or of the air circulation type, and the present invention relates to an electric heater of the conventional steam radiator unit form, and which is adapted to heat both by radiation and air circulation.

Among its objects, the principal feature of this invention is the provision in a radiator channel of means for causing a circulation of air within a given path, and the entrance of the air and its exit from the unit being at a point near the base of the unit consequently adjacent to the floor of the room. Another object is to provide an electric heater constructed of duplicate units enabling any number of units to be employed to construct a heater of the desired capacity; to provide in a heater of the air circulation type a resistance heating unit, the construction of which causes a circulation of air within the heater in a predetermined fixed path.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein:

Fig. 1 is a view in elevation partly in section of the preferred embodiment of my invention illustrating the co-operating radiator units forming the completed structure.

Fig. 2 is a cross sectional view taken on line 2-2 of Fig. 1 illustrating one of the resistance units.

Fig. 3 is a horizontal sectional view on line 3-3 of Fig. 1.

Fig. 4 is a view in bottom plan illustrating particularly the busbar connections be-

tween the resistance heating units, and Fig. 5 is a view in detailed side elevation of one of the resistance units removed from the heater.

Referring more particularly to the several views of the drawings wherein like characters of reference designate corresponding parts, 1 indicates a structure of the conventional well known steam or hot water radiator. This radiator is, as illustrated, built up of a plurality of independent units each including a hollow base 2 upwardly from which extend the tubular channels 3 of any desired number, it having been found that at least two channels are essential, one for an upward circulation and another for a downward circulation. At their upper ends, the channels 3 communicate with the common chamber 4. In the base of each unit there is transversely disposed across the chamber 2, at a point below the lower ends of the respective channels 3, a nested support or core 5 having wound thereon an electrical resistance, the windings 6 at a point below the lower ends of the channels A being closer together than the windings 7 located at a point below the lower ends of the channels B. From the terminal ends of the windings extend the busbars 8 for conveying electrical energy to the resistance. It has been discovered that by locating a resistance common to the lower ends of all of the channels 3, and making this resistance greater at a point below the ends of certain of the channels than it is at a point below the remainder of the channels, that an air circulation within a fixed path is maintained through the channels. In the present instance, the upward movement of the air is in the channels A and the downward movement is in the channels B, the air before leaving the radiator being further heated by the resistance unit provided with the windings 7. The air in its passage through the channels A and B heats the walls of said channels and in this manner heat is radiated from the walls of each channel, and on the air discharging from the channels B it passes into the enclosure to be heated from a point beneath the lowered edge of the chamber 2.

Each unit is a duplicate of the other, and the material forming the walls of the chamber 2 is at its opposite ends, in one instance, provided with an outwardly extending flange 9, and at its opposite end with a cor-

responding undercut recess 10, the flanged recess affording interfitting seat portions for receiving correspondingly formed end walls of an adjacent chamber. The upper end of the unit is provided at its opposite sides with the flanged openings 11 formed with similar flanged and under-cut portions as are the flanged under-cut portions 9 and 10 associated with the base of each unit. Current is supplied to the resistance units through a circuit formed by the lead wires 12, and in one of which wires is mounted a switch 13 controlled by a thermostat 14 of any well known type, the thermostat adapted for setting to make and break the electrical contact to maintain the radiator at the desired temperature.

With a construction of the present type, it will be apparent that a radiator of any number of units desired may be built up, and that a cheap and efficient form of heating resistance is employed arranged in such a manner as to insure a circulation of air within the channels of the radiator.

Having thus described my invention, what I claim as new and desire to protect by Letters Patent of the United States is:—

1. A heater of the circulation and radiation type including a chambered base, a pair of vertically disposed channels rising therefrom and connected at their upper ends and at their lower ends communicating through said chamber, said chamber opening to the atmosphere at a point below the point of connection afforded by it for the lower end of the channels, an electric resistance within the base of the heater and disposed transversely thereof across the lower ends of said channels at a point above the point of communication of the chamber with the atmosphere, said resistance at a point below one of said channels being greater than below the other of said channels.

2. A heater including a unit provided with a plurality of vertically disposed air circulation passages communicating at their upper ends and open at their lower ends, and an electric heating unit common to the lower ends of said passages, said unit being adapted to cause a return air circulation through said passages.

3. A heater including a unit provided with a plurality of vertically disposed air circu-

lation passages communicating at their upper ends and open at their lower ends, and an electric heating unit common to the lower ends of said passages, said unit creating a greater temperature at the lower ends of certain passages than at others thereby causing an upward circulation of air within the passages exposed to its greatest temperature and a downward circulation of air through the passages exposed to its lesser temperature.

4. A heater of the air circulation and radiation type including an upstanding member provided with a pair of vertically disposed air circulation passages connected at their upper ends, and opening at their lower ends within the base of said member, an electric heating element at the lower end of said passages, said element being of different heating capacities at the ends of the respective passages.

5. A heater of the air circulation and radiation type including an upstanding member provided with a pair of vertically disposed air circulation passages connected at their upper ends, and opening at their lower ends within the base of said member, an electric resistance unit carried by said member and common to the lower end of each passage, the resistance of said unit being greater at the lower end of one passage than at the lower end of the other.

6. A heater of the air circulation and radiation type including a plurality of duplicate interconnected radiator sections each including a vertically disposed member provided with a chamber at each end, and connected by a plurality of parallel spaced air circulating passages, the lower chamber opening to the atmosphere and the respective upper and lower chambers of each member communicating, an independent electric heating element in the lower chamber of each member and each element being disposed below the lower open end of the respective passages in said member, and the respective elements at a point below corresponding ends of adjacent channels being of a different resistance, and busbars detachably uniting the heating elements of adjacent members.

In testimony whereof I have signed my name to this specification.

AXEL JOHNSON.
